UNITED STATES PATENT OFFICE.

HENRY COLLIER SMITH, OF DETROIT, MICHIGAN.

POWER-HAMMER.

1,154,667.

Specification of Letters Patent. Patented Sept. 28, 1915.

Application filed November 20, 1914. Serial No. 873,114.

To all whom it may concern:

Be it known that I, HENRY COLLIER SMITH, a citizen of the United States, and a resident of Detroit, in the county of Wayne and State of Michigan, have invented a new and Improved Power-Hammer, of which the following is a specification.

This invention relates to power hammer and other blow-striking devices, and some of its objects are to provide means whereby the stroke of the hammer may be varied while the driving shaft is in motion; to provide means for automatically causing the stroke to become zero when the operator leaves the machine or ceases to control the hammer; and to improve the construction of the machine generally.

This invention consists in a hammer or other blow-striking device comprising a rotatable driving shaft, a crank shaft carried thereby and rotatable in respect thereto, the axis of the crank shaft being offset from that of the driving shaft, a crank pin carried by the crank shaft and arranged to drive a hammer, and a manually actuated member movable longitudinally of the crank shaft whereby the latter is caused to rotate and the stroke of the hammer to be varied.

It also consists in means for causing the axis of the crank pin to coincide with that of the driving shaft whenever the operator leaves the machine or ceases to operate the manually controlled means.

It further consists in the details of construction shown, described and particularly pointed out in the subjoined claims.

In the drawings, Figure 1 is a perspective view showing one embodiment of my invention. Fig. 2 is a vertical longitudinal section 40 of the hammer actuating mechanism. Fig. 3 is a fragmentary front elevation of the hammer with the actuating mechanism in normal position; that is, in position such that no stroke is imparted to the hammer. Fig. 4 is a section on the line 4—4 of Fig. 2. Fig. 5 is a section on the line 5—5 of Fig. 2. Fig. 6 is a fragmentary horizontal section showing the manner of connecting the bell crank to the longitudinally slidable 50 member in the driving shaft.

Similar reference characters refer to like parts throughout the several views.

In the present embodiment of my invention, the hammer 1 is shown in position to act upon an anvil 2 carried by a bracket 3, the construction of which is immaterial. Lo-

cated above the anvil bracket and secured to the post 4 or other support in any suitable manner is a hammer bracket 5, that includes the spaced bearing boxes 6, the inner of which may be adjacent an opening 7 in an upstanding arm 8 of the bracket. These boxes are supplied with caps 11 that serve to retain the bushings 12, in which a rotatable driving shaft, the details of which will be pointed out later, is mounted. The bearings may be of the ring-oiling type (the rings not being shown); and the pulley shaft is preferably provided with the circumferential flanges 13, the function of which is to direct lubricant that has passed through the bearings into the annular cups 14 at each end thereof. From the cups the lubricant flows through passages 15 back into the wells 16 of the bearing boxes.

The pulley shaft preferably comprises a front section 20 and a rear section 21 the opposite ends of which may be reduced to form the bearing portions 22 and 23, respectively, that rest in the bushings 12. The adjacent ends of the sections are faced at 24 and shouldered at 25, and may include the half pulley sections 26, spaced apart laterally from the main portion of the corresponding shaft-section and connected thereto at intervals by the perforated bosses 27. Through the latter the bolts 28, that secure the pulley sections rigidly together, pass. It will be understood that the pulley may be formed in various ways, that described being preferred since it results in a considerable saving of material. The adjacent ends of the pulley sections are hollowed out to form a chamber 30 that may be extended into the bearing portion 23 as indicated at 31.

Axially aligned with the pulley shaft and passing through the rear end thereof is a longitudinally shiftable rod 32, the front end of which may be provided with the guides 33 (Figs. 2 and 4) that embrace the key 34, the ends 35 of which are preferably supported in depressions in the wall of the chamber 30. The purpose of the guides and key is to prevent rotary movement of the rod 32 in respect to the pulley shaft. The rod is provided at its forward end with the spaced cross-walls 37, between which may be poured a Babbitt filling 38, having threads that engage with the threads 40 on the rotatable crank shaft 41, supported in a bearing formed in the portion 22 of the pulley shaft. One side of the rod 32 may

be hollowed out as indicated at 42 to allow the crank shaft to be nested therein. Forward longitudinal movement of the crank shaft through the bearing is prevented by the collar 43, that may be connected to it by the pin 44 and is in engagement with the face of a boss 45 formed on the wall of the chamber 30. In use the chamber 30-31 is preferably filled with lubricant which may be poured in through an opening provided with a plug 46 in alignment with the pin 44, this arrangement allowing a readily manipulation of the pin in assembling the parts.

It will be particularly noted that the axis 15 of the crank shaft is offset somewhat from that of the pulley shaft. The outer end of the crank shaft has formed integrally therewith, or rigidly secured thereto, the crank arm 50 from which the crank pin 51 projects, the axis of the crank pin being offset from that of the crank shaft the same amount that the axis of the crank shaft is offset from the axis of the pulley shaft (Fig. 5). It will therefore be seen that at one 20 point in the rotative movement of the crank shaft in respect to the pulley shaft the axis of the crank pin will be in coincidence with that of the pulley shaft, at which time the crank pin will be given no stroke; and that 25 at all other points the crank pin will be given a stroke, the length of which depends on the angular displacement of the crank shaft in respect to the pulley shaft at the particular instant, and the maximum of 30 which is equal to twice the amount the axis of the crank shaft is offset from that of the pulley shaft. The rotation of the crank shaft is, of course, caused by longitudinal movement of the rod 32. The crank pin 51 35 supports the connecting rod 52 bearing the leaf spring 53 from which may be suspended, by means of the loops 54 and strap 55, or in any other desired manner, the hammer 1, that may be guided in its reciprocatory movement by any suitable means 56.

The rod 32 may be moved longitudinally by mechanism, the particular construction of which will now be pointed out: The rear cylindrical end of the rod is received in the bore of a screw plug 60, threaded into a cavity formed in a housing 61; and the extreme rear end is preferably reduced and has threaded thereon the collar 62, between which and the plug and housing the hard 55 washers 63 and 64, respectively, may be interposed. The housing may be provided with the oil well 65 and oil passage 66, and the plug 60 may have its outer end formed to allow the application of a wrench whereby 60 it may be adjusted in the housing. A set screw 67 may be threaded into the housing and preferably bears against a soft metallic filler 68 whereby the plug is secured in any position of angular adjustment. 65 Upon opposite sides of the housing are

formed the guides 71 (Fig. 6) between which the vertically slidable members 72 bearing the pins 73 are guided. These pins are received in openings formed in the divided end 74 of the arm 75 of a bell-crank 76 that may swing about the pivot 77. The other arm of the bell-crank is preferably pivotally connected to the link 78, the lower end of which is in turn pivoted to the treadle 79 mounted on the fulcrum 80. It will be noticed that when pressure is applied to the foot-piece of the treadle the rod 32 is pulled outwardly whereby the crank arm 50 will be swung in clockwise direction (Fig. 5) to carry the crank pin 51 away from the axis of the pulley shaft. Should the foot of the operator be removed from the treadle, the rod 32 is immediately thrust forwardly by the tension spring 81, one end of which may pass through any one of the holes 82 in the bell crank, the other being preferably anchored to the bracket at 83. The forward movement of the rod causes the crank arm to turn in counterclockwise direction (Fig. 5), the amount of which is limited by the wall 84 of a groove 85 therein coming into contact with a pin 86 threaded or otherwise rigidly connected to the end of the pulley shaft. These parts are preferably so arranged as to come into mutual engagement only when the crank pin is in alignment with the axis of the pulley shaft, or when the stroke of the crank pin is zero. It will therefore be seen that when no pressure is applied to the treadle, the crank pin is automatically held in position such that no stroke is imparted to the hammer, and that the length of the stroke may be varied at will while the driving shaft is rotating.

It is clear that many changes may be made in the details of construction without departing from the spirit of my invention. For example, the nut may be arranged on the crank shaft instead of on the longitudinally movable rod. It is also clear that the invention is applicable to blow-striking machines other than those usually known as hammers, for instance, to percussion drills. I do not, therefore, wish to be limited otherwise than as indicated in the subjoined claims.

I claim:

1. A device for striking blows comprising a rotatable driving shaft, means for applying force to the driving shaft to cause it to rotate, a crank shaft supported thereby and rotatable in respect thereto, the axis of said crank shaft being parallel to and offset from that of said driving shaft, a member movable longitudinally of the driving shaft, said member and said crank shaft being so arranged that longitudinal movement of the member causes rotative movement of the crank shaft, a crank pin carried by said crank shaft, the axis of said pin being offset

from the axis of the crank shaft, a blow-striking member operatively connected to said crank pin, and manually operable means for moving the longitudinally movable member while the driving shaft is rotating whereby the axis of the crank pin is caused to recede from that of the driving shaft to increase the stroke of the blow-striking member.

10 2. A device for striking blows comprising a rotatable driving shaft, means for applying force to the driving shaft to cause it to rotate, a crank shaft supported thereby and rotatable in respect thereto, the axis 70
15 of said crank shaft being parallel to and offset from that of said driving shaft, a member movable longitudinally of the driving shaft, said member and said crank shaft being so arranged that longitudinal movement 75
20 of the member causes rotative movement of the crank shaft, a crank pin carried by said crank shaft, the axis of said pin being offset from the axis of the crank shaft, a blow-striking member operatively connected 80
25 to said crank pin, manually operable means for moving the longitudinally movable member while the driving shaft is rotating whereby the axis of the crank pin is caused to recede from that of the driving shaft to 85
30 increase the stroke of the blow-striking member, and means for normally holding the crank pin in position such that its axis is alined with that of the driving shaft.

3. A device for striking blows comprising a rotatable driving shaft, means for applying force to the driving shaft to cause it to rotate, a crank shaft supported thereby and rotatable in respect thereto, the axis of 100
35 said crank shaft being parallel to and offset from that of said driving shaft, a member movable longitudinally of said driving shaft and rotatable therewith, said member and said crank shaft being so arranged that longitudinal movement of the member 105
40 causes rotative movement of the crank shaft, a crank pin carried by said crank shaft, the axis of said pin being parallel to the axis of said crank shaft and offset therefrom the same distance the axis of the crank shaft is offset from the axis of the driving shaft, a blow-striking member operably connected to the crank pin, means connected to the rear end of said rod, in respect to which the rod is rotatable, for imparting longitudinal movement to the rod, means tending to move the last mentioned means in one direction whereby the 110
45 axis of the crank-pin is caused to approach that of the driving shaft, means for limiting the movement of the crank-pin in the direction stated, and manually operable means for moving the rod in the opposite direction to cause the axis of the crank pin to 115
50 approach that of the driving shaft, means for limiting the movement of the crank pin in the direction stated, and manually operable means for moving the longitudinally movable member in the opposite direction 120
55 while the driving shaft is rotating whereby the axis of the crank pin is caused to recede from that of the driving shaft and the stroke of the blow-striking member is increased.

60 4. A device for striking blows comprising

ing a rotatable driving shaft having a chamber formed therein, means for applying force to the driving shaft to cause it to rotate, a crank shaft supported thereby and rotatable in respect thereto, the axis of said 70
65 crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of 75
70 said pin being parallel to the axis of said crank shaft and offset therefrom the same distance the axis of the crank shaft is offset from the axis of the driving shaft, a blow-striking member operably connected to the crank pin, means tending to move the rod in one direction to cause the axis of the crank pin to approach that of the driving shaft, means for limiting the movement of the crank pin in the direction stated, and manually operable means for moving the rod in 80
75 the opposite direction while the driving shaft is in rotation whereby the axis of the crank pin is caused to recede from that of the driving shaft and the stroke of the blow-striking member is increased.

5. A device for striking blows comprising a rotatable driving shaft having a chamber formed therein, means for applying force to the driving shaft to cause it to rotate, a crank shaft supported thereby and rotatable in respect thereto, the axis of said 100
85 crank shaft being parallel to and offset from that of said driving shaft, a rod movable longitudinally of said driving shaft and rotatable therewith, the rod and crank shaft 105
90 including interengaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a blow-striking member operably connected to the crank pin, means tending to move the last mentioned means in one direction whereby the 110
95 axis of the crank-pin is caused to approach that of the driving shaft, means for limiting the movement of the crank-pin in the direction stated, and manually operable means for moving the rod in the opposite direction to cause the axis of the crank pin to 115
100 approach that of the driving shaft, means for limiting the movement of the crank-pin in the direction stated, and manually operable means for moving the rod in the opposite direction while the driving shaft is in rotation, whereby the axis of the crank-pin is caused to recede from that of the driving shaft and the stroke of the blow-striking member is increased.

6. A device for striking blows comprising a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including interengaging surfaces located in the chamber and so arranged that longitudinal movement of the rod causes rotative movement of the crank-shaft, a crank-pin carried by the crank shaft, the axis of said pin being parallel to the axis of said crank shaft and offset therefrom the same distance the axis of the crank shaft is offset from the axis of the driving shaft, a blow-striking member operably connected to the crank-pin, a housing in which the rear end of the rod is received and in respect to which the rod is rotatable, a collar on the rod and inclosed by the housing, an adjustable plug in the housing and adapted to exert pressure on the collar to take up longitudinal movement of the rod in the housing, means tending to move the housing in one direction whereby the axis of the crank-pin is caused to approach that of the driving shaft, means for limiting the movement of the crank-pin in the direction stated, and manually operable means for moving the housing in the opposite direction while the driving shaft is in rotation, whereby the axis of the crank-pin is caused to recede from that of the driving shaft and the stroke of the blow-striking member is increased.

7. A device for striking blows comprising a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft, a key contacting with the rod and serving to prevent the rod from rotating in respect to the driving shaft, the rod and the crank shaft including inter-engaging threads located in the chamber and so arranged that longitudinal movement of the rod causes rotative movement of the crank shaft, a crank-pin carried by the crank shaft, the axis of said pin being parallel to the axis of said crank shaft and offset therefrom the same distance the axis of the crank shaft is offset from the axis of the driving shaft, a blow-striking member operably connected to the crank-pin, means tending to move the rod in one direction to cause the axis of the crank-pin to approach that of the driving shaft, means for limiting the movement of the crank-pin in the direction stated, and manually operable means for moving the rod in the opposite direction while the driving shaft is in rotation, whereby the axis of the crank-pin is caused to recede from that of the driving shaft and the stroke of the blow-striking member is increased.

erable means for moving the rod in the opposite direction while the driving shaft is in rotation whereby the axis of the crank-pin is caused to recede from that of the driving shaft and the stroke of the blow-striking member is increased. 70

8. A device for striking blows comprising a rotatable driving shaft having a chamber formed therein, means for applying force to the driving shaft to cause it to rotate, a 75 crank shaft supported thereby and rotatable in respect thereto, the axis of said crank shaft being parallel to and offset from that of said driving shaft, means for preventing longitudinal movement of the crank shaft in 80 the driving shaft, a rod movable longitudinally of said driving shaft and rotatable therewith, the rod and crank shaft including inter-engaging surfaces located in the chamber and so arranged that longitudinal 85 movement of the rod causes rotative movement of the crank shaft, a crank-pin carried by the crank shaft, the axis of said pin being parallel to the axis of said crank shaft and offset therefrom the same distance 90 the axis of the crank shaft is offset from the axis of the driving shaft, a blow-striking member operably connected to the crank-pin, means tending to move the rod in one direction to cause the axis of the crank-pin 95 to approach that of the driving shaft, means for limiting the movement of the crank-pin in the direction stated, and manually operable means for moving the rod in the opposite direction while the driving shaft is in 100 rotation whereby the axis of the crank-pin is caused to recede from that of the driving shaft and the stroke of the blow-striking member is increased.

9. A device for striking blows comprising 105
a rotatable driving shaft having a chamber
formed therein, means for applying force
to the driving shaft to cause it to rotate, a
crank shaft supported thereby and rotatable
in respect thereto, the axis of said crank 110
shaft being parallel to and offset from that
of said driving shaft, means for preventing
longitudinal movement of the crank shaft in
the driving shaft, a rod movable longitudi- 115
nally of said driving shaft, means for pre-
venting the rod from rotating in respect to
the driving shaft, the rod and crank shaft
including inter-engaging surfaces located in
the chamber and so arranged that longitudi- 120
nal movement of the rod causes rotative
movement of the crank shaft, a crank-pin
carried by the crank shaft, the axis of said 125
pin being parallel to the axis of said crank
shaft and offset therefrom the same distance
the axis of the crank shaft is offset from the
axis of the driving shaft, a blow-striking
member operably connected to the crank pin,
means tending to move the rod in one di- 130
rection to cause the axis of the crank-pin to
approach that of the driving shaft, means 135

for limiting the movement of the crank-pin in the direction stated, and manually operable means for moving the rod in the opposite direction while the driving shaft is in rotation whereby the axis of the crank-pin is caused to recede from that of the driving shaft and the stroke of the blow-striking member is increased.

10. A device for striking blows comprising a rotatable driving shaft having a chamber formed therein, means for applying force to the driving shaft to cause it to rotate, a crank shaft supported thereby and rotatable in respect thereto, the axis of said 15 crank shaft being parallel to and offset from that of said driving shaft, a rod movable longitudinally of said driving shaft and rotatable therewith, the rod and crank shaft including inter-engaging surfaces located in 20 the chamber and so arranged that longitudinal movement of the rod causes rotative movement of the crank shaft, a crank arm and crank pin carried by the crank shaft, the axis of said pin being parallel to the 25 axis of said crank shaft and offset therefrom the same distance the axis of the crank shaft is offset from the axis of the driving shaft, a blow-striking member operably connected to the crank pin, means tending to 30 move the rod in one direction to cause the axis of the crank pin to approach that of the driving shaft, said crank arm and driving shaft constituting two members, a projection on one of the members arranged to 35 contact with a surface on the other member for limiting the movement of the crank pin in the direction stated, and manually operable means for moving the rod in the opposite direction while the driving shaft is in 40 rotation whereby the axis of the crank pin is caused to recede from that of the driving shaft and the stroke of the blow-striking member is increased.

11. A device for striking blows comprising a rotatable driving shaft having an enclosed chamber formed therein, means for applying force to the driving shaft to cause it to rotate, a crank shaft supported thereby and rotatable in respect thereto, the axis of 50 said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis 55 of said crank shaft and offset therefrom the same distance the axis of the crank shaft is offset from the axis of the driving shaft, a blow-striking member operably connected to the crank pin, means tending to move the rod in one direction to cause the axis of the 60

crank pin to approach that of the driving shaft, means for limiting the movement of the crank pin in the direction stated, manually operable means for moving the rod in the opposite direction while the driving shaft is in rotation whereby the axis of the crank pin is caused to recede from that of the driving shaft and the stroke of the blow-striking member is increased, said driving shaft having an opening leading to the 70 chamber therein through which lubricant may be supplied, and a removable plug for said opening.

12. A device for striking blows comprising a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a blow-striking member operably connected to the crank-pin, a housing connected to the rear end of said rod, in respect to which the rod 95 is rotatable, for imparting longitudinal movement to the rod, a guide arranged transversely of the housing, a member slideable in the guide, a lever having one arm in proximity to the slideable member, said member and said arm being pivotally connected, means tending to move the lever in one direction whereby the axis of the crank pin is caused to approach that of the driving shaft, means for limiting the movement of the 100 crank pin in the direction stated, and manually operable means for moving the lever in the opposite direction while the driving shaft is in rotation, whereby the axis of the crank pin is caused to recede from that of the driving shaft and the stroke of the blow-striking member is increased.

13. A device for striking blows comprising a rotatable driving shaft, means for applying force to the driving shaft to cause it 110 to rotate, a crank shaft supported thereby and rotatable in respect thereto, the axis of said crank shaft being parallel to and offset from that of said driving shaft, a member movable longitudinally of the driving shaft, 115 said member and said crank shaft being so arranged that longitudinal movement of the member causes rotative movement of the crank shaft, a crank pin carried by said crank shaft, the axis of said pin being off- 120

set from the axis of the crank shaft, a blow-striking member operatively connected to said crank pin, and arranged to reciprocate in a radial plane passing through the axis of the driving shaft, means for guiding the blow-striking member in its reciprocation, and manually operable means for moving the longitudinally movable member while the driving shaft is rotating whereby the axis of the crank pin is caused to recede from that of the driving shaft to increase the stroke of the blow-striking member.

14. A device for striking blows comprising a rotatable driving shaft, means for applying force to the driving shaft to cause it to rotate, a crank shaft supported thereby and rotatable in respect thereto, the axis of said crank shaft being parallel to and offset from that of said driving shaft, a member movable longitudinally of the driving shaft, said member and said crank shaft being so arranged that longitudinal movement of the member causes rotative movement of the crank shaft, a crank pin carried by said crank shaft, the axis of said pin being offset from the axis of the crank shaft, a blow-striking member operatively connected to said crank pin and arranged to reciprocate in a radial plane passing through the axis of the driving shaft, means for guiding the blow-striking member in its reciprocation, manually operable means for moving the longitudinally movable member while the driving shaft is rotating whereby the axis of the crank pin is caused to recede from that of the driving shaft to increase the stroke of the blow-striking member, and means for normally holding the crank pin in position such that its axis is alined with that of the driving shaft.

15. In combination, a rotatable driving shaft, means for applying force to the driving shaft to cause it to rotate, a crank shaft supported thereby and rotatable in respect thereto, the axis of said crank shaft being parallel to and offset from that of said driving shaft, a member movable longitudinally of the driving shaft, said member and said crank shaft being so arranged that longitudinal movement of the member causes rotative movement of the crank shaft, a crank pin carried by said crank shaft, the axis of said pin being offset from the axis of the crank shaft, a reciprocable member operatively connected to said crank pin, and manually operable means for moving the longitudinally movable member while the driving shaft is rotating whereby the axis of the crank pin is caused to recede from that of the driving shaft to increase the stroke of the reciprocable member.

16. In combination, a rotatable driving shaft, means for applying force to the driving shaft to cause it to rotate, a crank shaft supported thereby and rotatable in respect

thereto, the axis of said crank shaft being parallel to and offset from that of said driving shaft, a member movable longitudinally of the driving shaft, said member and said crank shaft being so arranged that longitudinal movement of the member causes rotative movement of the crank shaft, a crank pin carried by said crank shaft, the axis of said pin being offset from the axis of the crank shaft, a reciprocable member operatively connected to said crank pin and arranged to reciprocate in a radial plane passing through the axis of the driving shaft, means for guiding the reciprocable member in its reciprocation, and manually operable means for moving the longitudinally movable member while the driving shaft is rotating whereby the axis of the crank pin is caused to recede from that of the driving shaft to increase the stroke of the reciprocable member.

17. In combination, a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a reciprocable member operatively connected to said crank pin and arranged to reciprocate in a radial plane passing through the axis of the driving shaft, means for guiding the reciprocable member in its reciprocation, means tending to move the rod in one direction to cause the axis of the crank pin to approach that of the driving shaft, means for limiting the movement of the crank pin in the direction stated, and manually operable means for moving the rod in the opposite direction while the driving shaft is in rotation whereby the axis of the crank pin is caused to recede from that of the driving shaft and the stroke of the reciprocable member is increased.

18. In combination, a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-en-

gaging surfaces located in the chamber and so arranged that longitudinal movement of the rod causes rotative movement of the crank-shaft, a crank-pin carried by the 5 crank shaft, the axis of said pin being parallel to the axis of said crank shaft and offset there from the same distance the axis of the crank shaft is offset from the axis of the driving shaft, a reciprocable member oper- 10 ably connected to the crank-pin, a housing in which the rear end of the rod is received and in respect to which the rod is rotatable, a collar on the rod and inclosed by the hous- ing, an adjustable plug in the housing and 15 adapted to exert pressure on the collar to take up longitudinal movement of the rod in the housing, means tending to move the housing in one direction whereby the axis of the crank-pin is caused to approach that 20 of the driving shaft, means for limiting the movement of the crank-pin in the direction stated, and manually operable means for moving the housing in the opposite direction while the driving shaft is in rotation, 25 whereby the axis of the crank-pin is caused to recede from that of the driving shaft and the stroke of the reciprocable member is increased.

19. In combination, a rotatable driving 30 shaft having a chamber formed therein, means for applying force to the driving shaft to cause it to rotate, a crank shaft supported thereby and rotatable in respect thereto, the axis of said crank shaft being 35 parallel to and offset from that of said driving shaft, a rod movable longitudinally of said driving shaft, a key contacting with the rod and serving to prevent the rod from rotating in respect to the driving 40 shaft, the rod and the crank shaft including inter-engaging threads located in the chamber and so arranged that longitudinal movement of the rod causes rotative movement of the crank shaft, a crank- 45 pin carried by the crank shaft, the axis of said pin being parallel to the axis of said crank shaft and offset therefrom the same distance the axis of the crank shaft is offset from the axis of the driving shaft, a reciprocable member operably connected to the 50 crank-pin, means tending to move the rod in one direction to cause the axis of the crank-pin to approach that of the driving shaft, means for limiting the movement of the 55 crank-pin in the direction stated, and manually operable means for moving the rod in the opposite direction while the driving shaft is in rotation whereby the axis of the crank-pin is caused to recede from that of the driving shaft and the stroke of the reciprocable member is increased.

20. In combination, a rotatable driving 55 shaft having a chamber formed therein, means for applying force to the driving shaft to cause it to rotate, a crank shaft

supported thereby and rotatable in respect thereto, the axis of said crank shaft being parallel to and offset from that of said driving shaft, means for preventing longitudinal movement of the crank shaft 70 in the driving shaft, a rod movable longitudinally of said driving shaft and rotatable therewith, the rod and crank shaft including inter-engaging surfaces located in the chamber and so arranged that longitudinal 75 movement of the rod causes rotative movement of the crank shaft, a crank-pin carried by the crank shaft, the axis of said pin being parallel to the axis of said crank shaft and offset therefrom the same distance 80 the axis of the crank shaft is offset from the axis of the driving shaft, a reciprocable member operably connected to the crank-pin, means tending to move the rod in one direction to cause the axis of the crank-pin 85 to approach that of the driving shaft, means for limiting the movement of the crank-pin in the direction stated, and manually operable means for moving the rod in the opposite direction while the driving shaft is in 90 rotation whereby the axis of the crank-pin is caused to recede from that of the driving shaft and the stroke of the reciprocable member is increased.

21. In combination, a rotatable driving 95 shaft having a chamber formed therein, means for applying force to the driving shaft to cause it to rotate, a crank shaft supported thereby and rotatable in respect thereto, the axis of said crank shaft being 100 parallel to and offset from that of said driving shaft, means for preventing longitudinal movement of the crank shaft in the driving shaft, a rod movable longitudinally of said driving shaft, means for preventing the rod 105 from rotating in respect to the driving shaft, the rod and crank shaft including inter-engaging surfaces located in the chamber and so arranged that longitudinal movement of the 110 rod causes rotative movement of the crank shaft, a crank-pin carried by the crank shaft, the axis of said pin being parallel to the axis of said crank shaft and offset therefrom the same distance the axis of the crank shaft is offset from the axis of the 115 driving shaft, a reciprocable member operably connected to the crank pin, means tending to move the rod in one direction to cause the axis of the crank-pin to approach that of the driving shaft, means for limiting the movement of the 120 crank-pin in the direction stated, and manually operable means for moving the rod in the opposite direction while the driving shaft is in rotation whereby the axis of the crank-pin is caused to recede from that of the driving shaft and the stroke of the reciprocable member is increased.

22. In combination, a rotatable driving 125 shaft having a chamber formed therein, 130

means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank arm and crank pin carried by the crank shaft, the axis of said pin being parallel to the axis of said crank shaft and offset therefrom the same distance the axis of the crank shaft is offset from the axis of the driving shaft, a reciprocable member operably connected to the crank pin, means tending to move the rod in one direction to cause the axis of the crank pin to approach that of the driving shaft, said crank arm and driving shaft constituting two members, a projection on one of the members arranged to contact with a surface on the other member for limiting the movement of the crank pin in the direction stated, and manually operable means for moving the rod in the opposite direction while the driving shaft is in rotation whereby the axis of the crank pin is caused to recede from that of the driving shaft and the stroke of the reciprocable member is increased.

23. In combination, a rotatable driving shaft having an inclosed chamber formed therein, means for applying force to the driving shaft to cause it to rotate, a crank shaft supported thereby and rotatable in respect thereto, the axis of said crank shaft being parallel to and offset from that of the driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a reciprocable member operably connected to the crank pin, means tending to move the rod in one direction to cause the axis of the crank pin to approach that of the driving shaft, means for limiting the movement of the crank pin in the direction stated, and manually operable means for moving the rod in the opposite direction while the driving shaft is in rotation whereby the axis of the crank pin is caused to recede from that of the driving shaft and the stroke of the reciprocable member is increased.

24. In combination, a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a reciprocable member operably connected to the crank pin, a housing connected to the rear end of said rod, in respect to which the rod is rotatable, for imparting longitudinal movement to the rod, a guide arranged transversely of the housing, a member slideable in the guide, a lever having one arm in proximity to the slideable member, said member and said arm being pivotally connected, means tending to move the lever in one direction whereby the axis of the crank pin is caused to approach that of the driving shaft, means for limiting the movement of the crank pin in the direction stated, and manually operable means for moving the lever in the opposite direction while the driving shaft is in rotation, whereby the axis of the crank pin is caused to recede from that of the driving shaft and the stroke of the reciprocable member is increased.

25. In combination, a rotatable driving shaft having a chamber formed therein, means for applying force to the driving shaft to cause it to rotate, a crank shaft supported thereby and rotatable in respect thereto, the axis of said crank shaft being parallel to and offset from that of said driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a reciprocable member operably connected to the crank pin, a housing connected to the rear end of said rod, in respect to which the rod is rotatable, for imparting longitudinal movement to the rod, a guide arranged transversely of the housing, a member slideable in the guide, a lever having one arm in proximity to the slideable member, said member and said arm being pivotally connected, means tending to move the lever in one direction whereby the axis of the crank pin is caused to approach that of the driving shaft, means for limiting the movement of the crank pin in the direction stated, and manually operable means for moving the lever in the opposite direction while the driving shaft is in rotation, whereby the axis of the crank pin is caused to recede from that of the driving shaft and the stroke of the reciprocable member is increased.

26. In combination, a rotatable driving shaft having an inclosed chamber formed therein, means for applying force to the driving shaft to cause it to rotate, a crank shaft supported thereby and rotatable in respect thereto, the axis of said crank shaft being parallel to and offset from that of the driving shaft, a rod movable longitudinally of said driving shaft and rotatable therewith, the rod and crank shaft including inter-engaging surfaces located in the chamber and so arranged that longitudinal movement of the rod causes rotative movement of the crank shaft, a crank pin carried by the crank shaft, the axis of said pin being parallel to the axis of said crank shaft and offset therefrom the same distance the axis of the crank shaft is offset from the axis of the driving shaft, a reciprocable member operably connected to the crank pin, means tending to move the rod in one direction to cause the axis of the crank pin to approach that of the driving shaft, said crank arm and driving shaft constituting two members, a projection on one of the members arranged to contact with a surface on the other member for limiting the movement of the crank pin in the direction stated, and manually operable means for moving the rod in the opposite direction while the driving shaft is in rotation whereby the axis of the crank pin is caused to recede from that of the driving shaft and the stroke of the reciprocable member is increased.

27. In testimony whereof I have signed this specification in the presence of two subscribing witnesses.

HENRY COLLIER SMITH.
